[57] CLAIM

The ornamental design for a telephone, as shown and described.

DESCRIPTION

FIG. 1 is a rear perspective view of a telephone showing our new design;

FIG. 2 is a front elevation thereof;

FIG. 3 is a rear elevation thereof;

FIG. 4 is a side elevation thereof;

FIG. 5 is a top plan view thereof;

FIG. 6 is a bottom plan view thereof;

FIG. 7 is a rear perspective view of a second modified embodiment of the telephone illustrated in FIG. 1;

FIG. 8 is a front elevation thereof;

FIG. 9 is a rear elevation thereof;

FIG. 10 is a side elevation thereof;

FIG. 11 is a top plan view thereof;

FIG. 12 is a bottom plan view thereof;

FIG. 13 is a rear perspective view of a third modified embodiment of the form illustrated in FIG. 1;

FIG. 14 is a front elevation thereof;

FIG. 15 is a rear elevation thereof;

FIG. 16 is a side elevation thereof;

FIG. 17 is a top plan view thereof;

FIG. 18 is a bottom plan view thereof;

FIG. 19 is a rear perspective view of a fourth modified embodiment of the form disclosed in FIG. 1;

FIG. 20 is a front elevation thereof;

FIG. 21 is a rear elevation thereof;

FIG. 22 is a side elevation thereof;

FIG. 23 is a top plan view thereof; and

FIG. 24 is a bottom plan view thereof.
